(Cl. D14—3)

FIG. 3

The broken lines are for illustrative purposes only.

I claim:

The ornamental design for a golf-putting-equipment cart, as shown and described.
